METHOD OF SURVEYING WELLS AND APPARATUS THEREFOR

Willard J. Opocensky, Long Beach, Calif., assignor to Lane-Wells Company, Los Angeles, Calif., a corporation of Delaware

Application May 3, 1938, Serial No. 205,731

8 Claims. (Cl. 33—205)

My invention relates to a method and apparatus for surveying the course of well bores, and is particularly related to well-bore surveying wherein the rotation of a string of rods or tubing incidental to insertion into a well bore is determined in order to establish orientation of an inclinometer or other well bore surveying instrument lowered with and suspended from the string. Accordingly, among the objects of my invention are:

First, to provide a method and apparatus of this character which establishes graphically without mathematical calculations, the azimuth of readings or records taken by a well survey instrument as it is moved stage by stage into or out of a well bore on sucker rods, tubing or drill strings;

Second, to provide a method and apparatus of this character which minimizes the human error in that rotation of the string is automatically recorded on a photographic film for comparison and correlation with a corresponding record obtained from the survey instrument suspended from the string;

Third, to provide a method and apparatus of this character which is particularly applicable in conjunction with the apparatus and process set forth in the Stockenbury Patent No. 2,088,539 wherein, in effect, a predetermined point on the pipe or tubing string is carried along the pipe as it is inserted into or removed from the well bore;

Fourth, to provide a novelly arranged portable apparatus adapted to be set on the derrick floor having a pin which, by mere insertion into a sighting clamp employed in the above identified patent, indicates automatically the amount that the pipe has rotated incidental to a particular longitudinal movement;

Fifth, to provide a process and apparatus of this character which materially reduces the time required, as well as increases the accuracy of well bore surveys;

Sixth, to provide an apparatus of this character which does not interfere with the usual operation in and about the derrick floor during running in or withdrawing the tubing or the like, with which the survey is accomplished; and

Seventh, to provide an apparatus of this character which is durable and efficient in its action even under adverse conditions of use.

With the above and other objects in view, as may appear hereinafter, reference is made to the accompanying drawings, subjoined description and appended claims:

Figure 1 is a substantially diagrammatic ele-

vational view showing the initial stand of tubing with a surveying instrument at its lower end and with the orienting and sighting clamp positioned thereon;

Figure 2 is a similar substantially diagrammatic view with my rotation indicator shown inserted into the lowermost clamp for the purpose of indicating the initial position of the survey instrument;

Figure 3 is a plan view of my rotation indicator and its pantograph supporting frame;

Figure 4 is an enlarged longitudinal sectional view through my rotation indicator, taken substantially through 4—4 of Figure 3;

Figure 5 is a transverse sectional view thereof taken through 5—5 of Figure 4;

Figure 6 is a diagrammatic view illustrating fragmentarily the mechanical drive for my rotation indicator and the electrical elements controlled thereby;

Figures 7 through 14 are reproductions of typical records obtained by my method and in part with my apparatus;

More particularly, Figure 7 is representative of a record obtained with my rotation indicator;

Figure 8 is a corresponding record as obtained from the survey instrument; and

Figures 9 through 14 are composite records wherein that of my rotation indicator and the survey instrument are shown superposed to facilitate comparison and to indicate their relation.

In Figures 1 and 2 there is indicated diagrammatically a rotary table 1 in which is secured a survey instrument case 2 containing a survey instrument 3 of any suitable design, but preferably one that indicates inclination and gives a record of the time at which the record was made. Instruments of this character are operated photographically—such a type is preferred. The instrument 3 is a well established product and is not part of the present invention, except as this is inter-related with the rotation indicator and the method whereby the records from the indicator and survey instrument are correlated.

The case 2 is attached to the lower end of a stand of drill pipe 4, tubing or sucker rod, as desired. In the case 2, preferably near its upper end, there is provided a tapered socket 5 adapted to receive a tapered pin, upon the extended end of which is supported a transit 6 adapted to be sighted upon a distant object, the azimuth of which is known, so that the azimuth or bearing of the survey instrument may be determined.

In addition, two clamps 7 are secured to the tubing string, one near the top and the other

near the bottom thereof. Each clamp is provided with a tapered socket arrangement 8. The axes of the tapered sockets 8 are brought into registry by means of a sight bar 9 which is adapted to be fit into the lowermost clamp, and a sighting telescope 10 adapted to be inserted into the uppermost clamp. The telescope 10 is provided with a cross hair adapted to be brought into registry with a line provided on the bar 9, and when so aligned the axes of the sockets 8 are likewise in vertical alignment.

Before lowering the tubing string into the well with the instrument suspended thereon my rotation indicator is inserted into the lowermost clamp in place of the sight bar 9, as shown in Figure 2, and a record obtained of this initial angle of the sight bar with respect to a fixed base on the derrick floor, as will be described in more detail hereinafter.

20 A pedestal 11 is suitably secured to the derrick floor and is provided at its upper end with a yoke 12 having upturned bracket elements 13 at its ends which journal a shaft 14. Journaled about axes passing at right angles to and intersecting the axis of the shaft 14, near each end, is a pair of pantograph arms 15 which are journaled at their extremities to a cross member 16. A second pair of pantograph arms 17 are hinged to the cross member 16 and at their extremities to a plate 18. The two sets of pantograph arms form parallelograms sharing a common end, namely, the cross member 16. This arrangement serves to maintain the plate 18, that is, a plane through its points of connection with the arms 17 at all times parallel with the axis of the shaft 14. The plate 18 defines a yoke 19 having upturned bearings 20, between which is journaled about an axis parallel with the shaft 14 a rotation recorder or indicator 21.

40 The rotation indicator is journaled on the bearings 20 by means of a body member 22 which is in the form of a circular relatively thick disc with a depending internally threaded flange into which is secured the upper end of a case 23. The case 23 is adapted to carry a motor driven camera mechanism 24 whereby a strip of film 25 may be fed periodically into a frame 26. The frame 26 registers with a lens assembly 27 secured in the body member 22.

50 Extending upwardly from the body member 22 is a short sleeve 28 which journals internally by means of bearings 29 a cylinder 30 open at its ends. The upper end of the sleeve 28 supports a cap 31 which is screwthreaded thereto and which, in turn, supports a clock mechanism 32. The clock mechanism is conventional except that it is provided with a double face, that is, an upper face readable from the top of the cap 31 and a lower face exposed to the interior of the cylinder 30 and lens system or assembly 27.

60 The cylinder 30 is provided with a radially outwardly extending arm 33 having a tapered extremity 34 adapted to be inserted in the sockets 8. The sleeve 28 is provided with a slot 35 adapted to clear the arm 33 and permit approximately half circular movement of the arm and cylinder, as shown best in Figure 5.

In order to protect the interior of the cylinder from a source of outside light, as well as to protect the bearings 29 from dirt and contamination, there is provided a ring 36 which fits between the body 22 and the cap 31 around the outside of the sleeve 28, there being complementary step portions at the upper and lower

ends of the ring coating with the body member 22 and the cap 31 respectively.

The upper end of the cylinder 30 is traversed diametrically by a hair line 37. The hair line coincides with or may be at right angles to the axis of the pin 33 so as to indicate at all times the angular relationship of the pin 33 with respect to the body 22 and the photographic film 25.

The case 23 contains a motor, either spring driven or electrically driven (not shown), which not only drives the photographic film but operates a series of contacts to accomplish a predetermined series of operations. Reference is directed particularly to Figure 6 wherein there is illustrated diagrammatically a drive shaft 41 which operates through a suitable intermittent drive arrangement 42, a countershaft 43 suitably associated with the camera feeding mechanism for the photographic film 25. The shaft 41 or another shaft operatively associated therewith is provided with a control wheel 44 having a single notch therein adapted to be engaged by a catch 45 provided at the end of a shaft 46 which protrudes through the bottom of the case 23 and is provided with a knob 47 which may be manually engaged for the purpose of lifting the catch 45 from the control wheel 44 and permitting a single revolution before the catch re-engages, there being a spring 48 arranged to urge the catch 45 into engagement with the control wheel 44.

The control wheel 44 is suitably associated with a pair of cam wheels 49 and 50 which control switches 51 and 52, respectively. One side of each switch 51 and 52 is connected through a master switch 53 to a battery 54, or other source of electric power. The switch 53 is also connected through indicator lights 55 to ground. This light is adapted to be on whenever the switch 53 is closed to indicate that the system is ready for operation. The switch 51 is connected through a warning light 55 to ground, and switch 52 through a second warning light 56 to ground. The switch 52 is also connected through a plurality of photographic bulbs 57 to ground, said bulbs being mounted inside the cylinder 29 around the lens mounting 27, as shown in Figures 4 and 5.

The indicating light 54 and the warning lights 55 and 56, as well as the switch 53 and battery 54, may be contained within a housing 58 supported from the pedestal 11, the remaining mechanism being contained in the case 23 and conductor wires leading from the housing 58 to the case 23. The operation of the circuit shown in Figure 6 will be described in more detail hereinafter.

The pedestal 11 is provided with an adjustable arm 59 terminating in a multiple ribbed support 60 upon which the extremities of the pantograph arms 17 may rest when the rotation indicator is not in use, as indicated by dotted lines in Figure 2.

Operation of my rotation indicator is as follows: The body 21, while movable within certain limits in a horizontal plane, is not rotatable and therefore it, as well as the face of the clock 32, maintains a constant bearing. The pin 33, however, and cross hair 37 is free to rotate within a half circle. Consequently, when the survey instrument 3 has been oriented by the telescope 6 and the clamps 7 have been aligned one with the other, the pin 33 may be inserted in the socket 8 and a photograph taken of the hair line 37 and clock 32 to indicate what angle the hair line 37

- assumes with respect to the clock face. A reproduction of such record is shown in Figure 7 wherein the peripheral markings 71 indicate the clock face, the triangular pointers 72 and 73 indicate the extremities of the clock hands, and the radial line 74 indicates the angular displacement of the pin 33 and hair line 37 with respect to any point on the clock face, such as the character XII.
- 10 The record obtained by the survey instrument may take the form shown in Figure 8, in which the concentric circles 81 represent the degrees of inclination, and the radial marks 82 the reference points with respect to the tapered socket 5, there being one such reference point 82a which is distinguished from the others. In addition, a cross hair marking 83 indicates the position of the plumb bob or other inclination indicating means, and the clock dial 84 serves to establish the time at which the photograph is taken, for correlation with the clock record taken in Figure 7.
- 15 In actual practice there is a pause between the insertion of each stand, while the succeeding stand is made up on the string, the clamps 7 are positioned and the sighting member 10 alined with the bar 9. The mechanism of the inclinometer instrument 3 is arranged to make records with sufficient frequency that at least one record is obtained during the necessary interval in which the tubing string is at rest. It is during such interval, of course, that the rotation recorder or indicator is inserted into the tapered socket 8, so that by comparing the time indicated by the clock 32 with the photographic record 84 of the clock in the survey instrument it is possible to correlate the two records. The initial record obtained in the rotation indicator, as shown in Figure 7, establishes the relationship 20 of the initial survey instrument record shown in Figure 8, with respect to the known azimuth as determined by the transit 6. It is immaterial what angle the clamps 7 may take with respect to the transit 6 as long as it is within the range 25 of movement of the pin 33. Thus the image 74 of the hair line 37 indicates an angle of approximately 30 degrees, and the reference indicia on the survey instrument record in Figure 8 would be set at 30 degrees also to correspond. Initially 30 the upper clamp 7 is in vertical alinement with this position, but as the first stand of tubing, or the like, is lowered into the well the tubing may rotate, as for example, in Figure 9, the tubing may have rotated from the position shown in 35 Figure 7 to a position wherein the angle of the hair line image 74 is now slightly to the left, or approximately 40 degrees from its original position. Consequently the reference point 82 of the survey instrument record would be rotated 40 correspondingly. For convenience, the records are shown superposed, and in practice they may be superposed photographically after the films from the survey instrument and rotation indicator are developed.
- 45 In Figure 10 the composite record indicates that the tubing string has rotated to the right about 20 degrees from the position shown in Figure 9. In Figure 11 the indication is that the tubing has rotated about 40 degrees to the left from that in Figure 10, and in Figure 12 another 30 degrees from that shown in Figure 11. Theoretically the rotation indicator could be designed for rotation of 360 degrees, or at least over 180 degrees, and the socket 8 made double-ended.
- 50 In practice, however, it is inconvenient to per-

mit the clamps 7 to progress around the pipe for the reason that the derrick man cannot conveniently sight from all positions. It is, therefore, customary to maintain the clamps within a predetermined angulation from their initial position. Consequently, as the rotation of the tubing string progresses beyond the desired amount, the clamps are offset 90 degrees with respect to each other by placing a 90-degree adapter in the lowermost clamp before alining the sighting tube 10 with the bar 9. The effect of this operation is shown in comparison of Figures 12 and 13, wherein the tubing is actually advanced to the left from the position shown in Figure 12 about 20 degrees, but instead of alining the hair line 74 with the mark 82a it is alined with one of the marks 82. In practice, a record is made every time a 90-degree shift is made, but this is not necessary for the reason that the displacement of the hair line by reason of such shifting is greater than any amount that the pipe would normally move and, therefore, the arbitrary shift is self-evident from inspection of the series of records.

55 After the bar 33 is inserted in the socket 8 the trigger or push button 47 is raised, switch 53 having first been closed so that the signal light 54 is on. The recording mechanism is therupon caused to operate: first, the warning light 55 is operated, indicating that the record is about to be made; light 55 then goes off and at the same time light 56 goes on along with the photographing light 57, indicating that the photographic record is actually being made. As soon as light 56 goes off and light 55 again comes on, the operator knows that the record is completed and he may withdraw the pin 33 from the socket. Very little actual time is required for this operation.

60 Though I have shown and described a particular construction, combination and arrangement of parts and portions, and a certain method and mode of operation, I do not wish to be limited thereto but desire to include in the scope of my invention the constructions, combinations and arrangements, and methods of operation substantially as set forth in the appended claims.

I claim:

65 1. In a system of surveying well-bores wherein a string of pipes or rods is lowered or raised in stages and the rotation incidental thereto is determined by means of clamp elements and sighting devices which are removably inserted therein, an apparatus for recording the amount of such incidental rotation, comprising: an instrumentality adapted to be inserted in said clamps in the manner of said sighting devices; so as to occupy a fixed azimuthal relation thereto; a frame revolvably supporting said instrumentality, means for maintaining said frame at a predetermined azimuth; and coacting means on said frame and said instrumentality for recording the angular movement of said instrumentality relative to said frame required for insertion in said clamps.

70 2. In a system of orienting a pipe or rod string by stands into a well-bore wherein a clamp is positioned at the top of a stand of pipes or rods alined with another clamp, positioned at the bottom of said stand and then lowered with the stand, the combination of a rotation recording device comprising: a frame structure adapted to maintain a fixed azimuthal relation with the string of pipes or rods; a member mounted in said frame structure for angular movement about

- an axis substantially parallel with said string and adapted to fit said clamp; and coacting means on said frame structures and said member for recording the angular movement of said member relative to said frame structure required to fit the same into said clamp.
3. In a system of orienting a pipe or rod string by stands into a well-bore wherein a clamp is positioned at the top of a stand of pipes or rods alined with another clamp and then lowered with the stand, the combination of a rotation recording device comprising: a fixed support adapted to be fastened near said string; a housing structure; a parallel motion linkage connecting the housing structure and support, and adapted to permit movement of said housing while restraining the same against rotation with respect to said support, whereby said housing is maintained in a fixed index plane; an instrumentality rotatably supported by said housing and adapted to fit said clamp; scale means carried by said instrumentality and said housing for indicating relative angular movement therebetween; and means for recording, at intervals, the positions of said scale means.
4. In a system of surveying well bores wherein a string of pipes or rods is lowered or raised in stages and the rotation incidental thereto is determined by means of clamp elements and sighting devices which are removably inserted therein, of an apparatus for recording the amount of such incidental rotation, comprising: a camera, a mounting therefor securing said camera against movement in azimuth but permitting movement in a horizontal plane; means rotatably supported relative to said camera, including an arm adapted to fit said clamps in place of said sighting devices so as to occupy a fixed azimuthal position relative thereto and a reference marker rotatable with said arm and adapted to be photographed by said camera to indicate the azimuthal relation of said arm with respect to the fixed position in azimuth of said camera.
5. An apparatus of the class described, comprising: a camera; a mounting therefor restraining said camera against rotation in azimuth and including a parallel movement linkage to permit movement of said camera in a horizontal plane, and journal means permitting movement of said camera about a horizontal axis whereby said camera may be directed vertically; and means mounted for rotation in azimuth about a vertical axis concentrically with respect to said camera and including an element adapted to be photographed by said camera for indicating the azimuthal relation of said means and camera.

6. An apparatus, as specified in claim 5, where-
in a clock is positioned with its face within the photographic range of said camera whereby a series of photographs taken of said camera may be distinguished chronologically. 5

7. In a method of surveying well bores, the steps comprising moving a recording instrument within and along a bore in stages on a pipe or rod string; recording by said instrument at a number of points along the bore a series of composite records of the inclination of the bore, the direction of said inclination with respect to a known plane through said instrument, and the time of each recording; recording by a separate instrument outside of and adjacent the upper end of said bore a series of composite records of the angular rotation of said known instrument plane and string with respect to a known azimuth plane, and the time of each recording; 10 the records of direction of inclination and angular rotation comprising marks which define angles, selecting from said series of records an inclination record and an angular rotation record having substantially contemporaneous time records thereon; superposing one of said selected 15 records on the other with the respective direction and rotation marks aligned for reading; and reading from said superposed records the amount of inclination and its direction with respect to said azimuth plane to determine the 20 inclination and direction of inclination of the bore at a desired point therealong. 25

8. In a system of surveying well bores, the combination comprising a survey instrument adapted to be moved within and along a bore 30 in stages on a pipe or rod string, said instrument including a recording device for recording on a single record the inclination, the direction of inclination of said bore with respect to a known plane through said instrument, and the time of 35 each inclination recording; and a second recording device outside of and adjacent the upper end of said bore and adapted to be connected to said string for recording on a single record the angular rotation of said known plane and string with 40 respect to a known azimuth plane, and the time of each angular rotation recording; the contemporaneous recordings of said two devices being a series of marks defining angles, and adapted to 45 be superposed with marks aligned for indicating 50 the amount and direction of inclination of a bore with respect to said azimuth plane at a desired point therealong. 55
